[57] CLAIM

The ornamental design for a smoke chamber, as shown and described.

DESCRIPTION

FIG. 1 is a left front perspective of a smoke chamber, showing my new design;

FIG. 2 is a front elevational view, thereof;

FIG. 3 is a rear elevational view, thereof;

FIG. 4 is an elevational view of one side, the opposite side elevational view being a mirror image, thereof;

FIG. 5 is a top plan view, thereof;

FIG. 6 is a bottom plan view, thereof; and,

FIG. 7 is a left front perspective as in FIG. 1, taken to a reduced scale, the broken line representation of the fireplace fire box, transition piece, and flue pipe being shown solely for illustrative purposes, forming no part of the claimed design.
